APPARATUS FOR TREATING TEXTILE MATERIALS

Filed Sept. 21, 1929

FIG. 2.

Charles De Witte
INVENTOR

By Otto W. Wink
his ATTORNEY

UNITED STATES PATENT OFFICE

CHARLES DEWITTE, OF BRUSSELS, BELGIUM

APPARATUS FOR TREATING TEXTILE MATERIALS

Application filed September 21, 1929, Serial No. 394,337, and in Belgium September 25, 1928.

My invention relates to the apparatuses which are used for bleaching, dyeing, finishing or otherwise treating textile materials, from vegetable, animal or artificial origin in the form of hanks, or fabrics for example and more especially to the apparatus of that kind in which the liquid of treatment is put into circulation in a vat containing the materials to be treated.

Its main object is to provide means in order to increase the quantity of the materials which are treated in a single operation in a vat having given dimensions whilst keeping favorable technical conditions from the point of view of the circulation of the liquid, of the concentration of the liquid and of the action of the latter on the materials to be treated.

A further object is to reduce the numerous manipulations which are necessary in the systems which are now in use to the single operation of suspending the hanks or fabrics to supports on which they can be kept till after the complete treatment so as to avoid supplementary manipulations between the several operations or treatments.

And another object is to simplify the construction of the apparatus in reducing to a minimum the number and the complication of the different constituting elements.

With these objects in view, the invention essentially consists in the special combinations and arrangements of parts which will be hereinafter fully described and ascertained and pointed out in the appended claims.

Referring to the annexed drawings:

Fig. 1 is a cross-section through an apparatus which is adapted for treating textile materials, for example, a dyeing or bleaching apparatus provided with the usual devices for the circulation of the liquid. In this figure the supports for the material have been shown but the material has not been represented for sake of clearness.

Fig. 2 is a separate view in perspective of the supporting frame of the materials to be treated as used in the apparatus shown on Figure 1.

Fig. 3 is a section through the great axis 50 of the apparatus and showing the arrange-

ment of the supports for the material in the grooves of the supporting frame.

As it is well known, in the apparatus which have been used till now for dyeing, bleaching or otherwise treating textile materials by 55 means of a circulating liquid, the materials to be treated have generally been placed in the vat of treatment on suitable supports, for instance, on perforated bottoms slid in grooves provided in or on the walls of the vat or they 60 have been suspended to movable supports maintained at their upper and at their lower part in vertical grooves of frames adapted to be arranged in the vat of treatment. The free disposition of the materials to be treated 65 on perforated bottoms presents the drawback that, in the case of materials in the form of hanks or of fabrics, a settling on the bottom is produced which interferes not only with the quality of the products but also with the 70 repartition and with the uniform and regular action of the liquid of treatment. This produces the entangling of the threads and unbleached stains. Moreover the suspension of the materials in the vat of treatment by means 75 of movable supports which are juxtaposed at the upper part and at the lower part of the apparatus in vertical grooves of supporting frames, has the inconvenience of forming between the different paths of the material, for 80 instance, between the successive folds of a fabric band or between the hanks, lost spaces which are equal to the diameter of the movable supports, which diminishes considerably the quantity of materials adapted to be treat- 85 ed in the apparatus in one operation.

Moreover as only a small quantity of material can be treated at the same time, a considerable expense of labor is necessary.

Those inconveniences are removed accord- 90 ing to the present invention in view of the fact that it is made use in combination with the vat, in which the liquid of treatment is caused to circulate, of a supporting frame provided on its longitudinal inner walls with 95 a plurality of horizontal superposed grooves in which supporting rods can be slid through the open extremity of the frame or in holding them obliquely. Those rods are introduced successively in the superposed horizontal 100

grooves of the frame, keep the thread or the fabric hanging in vertical, parallel and adjacent layers, so that the different vertical layers of the material to be treated, or at least 5 groups of layers can eventually get into contact, the thickness of the main part of the supports being compensated by the fact that instead of being juxtaposed, they are superposed and slightly displaced one to each other 10 in the horizontal direction according to the thickness of the supported materials.

In Figure 1, the apparatus shown as an example, comprises a vat in concrete 1 (or in any other suitable material) which forms on 15 its longitudinal internal faces bearing surfaces 2 for a movable frame 3 which for instance may be also in concrete. This frame 3, which is shown separately on figure 2, is formed by two longitudinal beams 4 which 20 are provided on their inner faces with a series of horizontal superposed grooves 5 which may be traced direct in the concrete or be formed, as shown on the drawings, by inoxidizable blades 5a which are embedded in the concrete or by tiles or equivalent elements fixed in the concrete. The longitudinal beams 4 are connected by two transverse beams 6 and 7. The beam 6 which is arranged at the rear 25 side of the frame is of the same height as the longitudinal beams, whilst the beam 7 which is arranged in front of the frame is not so high so as to keep free the end of the grooves 5.

Supports 8 in wood or in another substance for instance of a round form may be introduced in the grooves 5 in order to sustain the material 9 to be treated. Rings 10 are fixed in each of the corners of the upper portion of the frame 4 in order to allow 30 its lifting by means of any lifting device not shown.

The vat 1 is provided with the usual means for the circulation of the liquid of treatment. In the example shown, on the bottom, supports 11 which sustain plates 12 pierced with openings 13 are arranged. Under the false bottom formed by the plates 12 is arranged a transverse pipe 14 on which 35 perforated pipes for the liquid of treatment are branched. This distribution system is connected by a pipe 16 to a pump 17 connected by a pipe 18 to pipes 19 formed in the wall of the vat 1 above the movable frame 3. Those pipes 19 open in the vat by openings 20 arranged on the whole periphery of the vat. The pipe 18 is in communication with a pipe 21 for the liquids to be recovered or for the introduction of the bath. Valves 22 and 23 are placed in the pipe 18 in order to 40 allow the liquid sucked from the vat 1 by the pump 17 to be sent either again in the vat, when the valve 22 is opened and the valve 23 closed, so as to obtain a continuous circulation in the vat, or to a recovering vessel (not shown) connected to the pipe 21

when the valve 22 is closed, whilst the valve 23 is opened.

The vat 1 can be provided, as usual, with a steam pipe 24 in which a valve 25 is inserted, with a drain valve 26 arranged in a corner of the vat and with a cover 27.

The apparatus thus constructed is used in the following manner.

The movable frame 4 is placed on four pillars (not shown) of a suitable height. 75 The materials to be treated (hanks, or fabrics for example) are arranged on the supports 8 and the latter are introduced through the open face of the frame 3 in the grooves 5. A first support 8 carrying the material 9 to be treated suspended as shown on Fig. 2, is introduced, in the lowest groove 5 of the frame 3 (Fig. 3) and is slid till the end of the groove against the beam 6 of the frame; a second similar support carrying also material to be treated is afterwards introduced in the second groove arranged immediately above the first and is slid as close as possible to the beam 6 of the frame; successively a support 8 is introduced in each of the upper grooves till each of the latter has received a support, afterwards a new support is introduced in the lowest groove 5 (Fig. 3) and it is continued on that way till all the frame is full. It is easy to understand that under those conditions, as shown on Fig. 3, the distance comprised between two supports 8 juxtaposed in the same groove 5, for instance in the lower groove of the frame is occupied by the material suspended on the supports which are introduced in the different superposed grooves with which the frame is provided. In other words, there is no lost space unused between two supports 8 arranged in a same horizontal groove 5, viz situated in the same horizontal plane; this space is occupied by the material suspended on the supports 8 which are slid in the upper grooves and which are arranged in vertical planes displaced one to each other in the direction of the grooves of a quantity corresponding to the thickness for example of the material or of any other suitable quantity.

When the movable frame has been completely filled in that way, it is lifted by means of a crane or of a travelling bridge (not shown) which conducts it above the vat 1 of treatment and causes it to descend in that vat and to rest on the bearing surfaces 2.

The vat is afterwards filled with liquid; the valve 23 is closed, the valve 22 is opened and the pump 17 is put into motion. The liquid is put into circulation in that way from top to bottom through the material 9 contained in the vat or in the opposite direction according to the sense of rotation of the pump.

When the treatment is completed, the liquid is exhausted by the valve 26. In the

case where it must be used again, instead of opening the valve 26, the valve 22 is closed and the valve 23 is opened so that under the action of the pump 17 the liquid is sent through the pipe 21 into a special vessel (not shown) from which it will be again returned in the vat 1 for a new operation.

When the treatment is completed, the apparatus is emptied the material remains during a certain period of time in the vat in order to drip. The crane is afterwards brought above the frame 4 and removes the latter and the supports 8 by means of the hooks 10. The frame is placed again on four pillars in order to finish the dripping, and the supports 8 which are still loaded with their hanks are removed from the frame in an inverted order than that into which they had been introduced and pass to the dryer without any other manipulation. The materials are in that way, rinsed, bleached, acidulated etc. and dried on the same supports on which they have been placed during the different operations, those supports being in materials which are adapted to resist the physical and chemical treatments hereabove indicated.

It is obvious that the hereabove indicated method of inserting the supporting rods in the grooves of the frame has only been given by way of example. For instance, instead of placing the first supporting rod of each group in the lowest groove, and then superposing successively the supporting rods in the superposed grooves it would be facultative to place this first rod in the highest groove and then successively the other supporting rods in the lower grooves, without departing from the nature of the invention.

What I claim is:

1. In an apparatus for the treatment of textile materials in the form of hanks or of fabrics by causing the liquid of treatment to circulate, a vat of treatment, means for causing the liquid of treatment to circulate in the vat, supports for the materials to be treated on which those materials are freely suspended in vertical layers and means whereby those supports are juxtaposed in series in the vat at different levels whereby the vertical layers of materials are juxtaposed by groups substantially in contact one with each other.

2. In an apparatus for the treatment of textile materials suspended in vertical layers by causing the liquid of treatment to circulate, a vat, means for causing the liquid of treatment to circulate in the vat, supports for the materials to be treated on which those materials are freely suspended, a movable frame open at one end and adapted to be placed in the vat of treatment, this frame being provided on the inner faces of its longitudinal beams, with horizontal superposed grooves for the supports of the materials to be treated, whereby those supports when slid

successively in those superposed grooves cause the juxtaposition by groups of the vertical layers of materials.

3. In an apparatus for the treatment of textile materials in vertical layers by causing the liquid of treatment to circulate, a vat of treatment, bearing surfaces formed on the internal longitudinal faces of that vat, means for distributing and causing the liquid to circulate in that vat, a movable frame adapted to be arranged in that vat on the bearing surfaces, this frame being provided on the inner faces of its longitudinal beams with horizontal superposed grooves, supports for the materials to be treated on which those materials are freely suspended, those supports being adapted to be slid in the superposed grooves of the frame at different levels, whereby the materials to be treated are suspended in the frame at different levels and in the form of juxtaposed vertical layers substantially in contact one with each other.

4. In an apparatus for the treatment of textile materials in vertical layers, by causing the liquid of treatment to circulate, a vat of treatment, this vat being provided on its inner longitudinal faces with horizontal bearing surfaces, means for distributing and causing the liquid of treatment to circulate in the vat, a movable supporting frame adapted to rest on the bearing surfaces of the vat, this frame comprising two longitudinal beams provided with superposed horizontal grooves and two beams arranged at the extremities and having different heights, one of those beams being arranged above the grooves provided in the longitudinal beams, and supports for the material to be treated adapted to be slid in those grooves, whereby, in view of the superposition of the said supports by series in the successively superposed grooves of the frame the material is suspended in vertical juxtaposed layers substantially in contact one with each other.

In testimony whereof I have affixed my signature.

CHARLES DEWITTE.
